UNITED STATES PATENT OFFICE.

JAMES HARTNESS, OF SPRINGFIELD, VERMONT.

TELESCOPE.

1,045,142.

Specification of Letters Patent.

Patented Nov. 26, 1912.

Application filed November 25, 1911. Serial No. 662,340.

To all whom it may concern:

Be it known that I, JAMES HARTNESS, a citizen of the United States, and resident of Springfield, in the county of Windsor 5 and State of Vermont, have invented certain new and useful Improvements in Telescopes, of which the following is a specification.

This invention has relation to equatorial refracting telescopes.

10 The primary object of the invention is to provide a structure in which observations may be made without discomfort to the observer, without limiting his range of observation, and without detriment to instrumental precision. Speaking generally, this is accomplished, according to my invention, by providing a closed structure of non-conducting material, having a dome or turret arranged to move about an axis parallel 15 with the axis of the earth. The space within the structure may be heated in the winter and cooled in the summer, irrespective of outside atmospheric temperatures, so that the observer may work at all times in an agreeably tempered atmosphere. The telescope tube is located outside the dome and is pivoted at its inner end to the turret or dome so as to swing about an axis perpendicular to the axis of the dome or to a line 20 parallel to said axis. The eyepiece is substantially in alinement with the pivot, and is located within the dome or turret, the bundle of light rays being reflected from the object glass to the eyepiece by a single prism 25 or reflector located at the elbow or junction of the axes of the eyepiece and the telescope tube. As a result of this construction, the tube is swung about its pivot to obtain the desired angle of declination, and the 30 turret or dome, with the tube supported thereby, is rotated about the axis to secure the desired angle of right ascension.

Inasmuch as the tube is pivoted at one end, it is desirable not only to counterweight 35 it, but also to provide a stay or brace for supporting and bracing the free end, and this is accomplished by a weighted arm pivoted to the turret or dome on the declination axis of the tube, but on the side of 40 the turret opposite that to which the tube is pivoted, and connected to the free end of the tube at one or more points. Thus the pivot for the tube is relieved of a part of the weight of the tube as well as of all 45 torsional strains. The counterweighted arm acts wholly as a support or counterpoise for

the free end of the tube in one position of the turret, and, when the turret is in another position, it acts wholly as a brace, while at other times it acts partially as a 60 brace and partially as a support for the tube, these functions depending upon the position of the inclined turret.

The turret or dome is preferably supported upon rolls, of which there are two 65 sets. One set of rolls maintains the axis of the turret in parallelism with the earth's axis, and the other set holds the center of the turret in a fixed position relatively to the supporting structure or building to 70 facilitate convenience in measurement of the angular position of the telescope as to hour position or right ascension. Some of the rolls of the second set may be utilized for effecting the rotation of the turret, for securing the desired angle of right ascension, or for following a celestial body. To this end, a motor and suitable power-transmitting connections are employed, and controlling or governing devices therefor are located within the dome or turret so that they may, if desired, be manipulated by the observer while the latter has his eye at the eyepiece. In order that the hour position of the tube may be easily determined, I preferably employ a ring or hour circle which is supported by the dome, and an index, on the base or supporting structure. In practice, I preferably mount the circle or ring so that it may be rotated relatively to the 80 dome, and for convenience locate two diametrically opposite indexes on the dome. 85

Any convenient mechanism under control of the observer is provided for moving the telescope to the desired angle about its 95 declination axis, and for this purpose the illustrated embodiment of the invention is provided with worms operated by a hand wheel and engaging a worm wheel connected to the tube adjacent its elbow. 100

In addition to the features which have been briefly referred to, the invention comprises other features of construction and arrangement which are illustrated upon the drawings, described in the following specification, and pointed out in the claims. 105

Referring to the drawings,—Figure 1 represents a side elevation of the telescope and a longitudinal vertical section of the supporting structure. Fig. 2 represents a floor 110 plan of the upper compartment which the observer occupies. Fig. 3 represents a floor

plan of the lower compartment of the housing. Fig. 3^a represents a longitudinal vertical section through the turret in which the telescope is mounted. Fig. 4 represents a section through the turret, indicated by line 4—4 in Fig. 1. Fig. 4^a represents a section through the turret on the plane indicated by line 4^a—4^a in Fig. 3^a. Fig. 5 represents an elevation, on a relatively small scale, of the 6 turret and telescope, the latter being arranged to point to the zenith. Fig. 6 represents a side elevation of the turret and telescope, and a portion of the housing. Fig. 7 represents an elevation of the rolls 10 for turning the turret, and a train of gears for driving the rolls. Fig. 8 represents another elevation of the same rolls with the train of gears in cross section. Fig. 9 represents a sectional view of clutch mechanism 15 for driving the train of gears represented in Figs. 7 and 8. Fig. 10 represents a side elevation, partly in section, of transmission gearing and clutch mechanism for driving the turret. Fig. 11 represents a horizontal 20 section on the plane indicated by line 11—11 of Fig. 10. Fig. 11^a represents a similar section showing a modification, (see sheet bearing Fig. 3^a). Fig. 12 represents a horizontal section on the plane indicated by line 25 12—12 in Fig. 10. Fig. 13 represents a section in the plane indicated by line 13—13 in Fig. 10. Fig. 14 represents a section in the plane indicated by line 14—14 in Fig. 10. Fig. 15 represents a vertical section in 30 the plane indicated by line 15—15 in Fig. 10. Fig. 16 represents a vertical section, on a larger scale, of a friction driving connection indicated in Fig. 10. Fig. 17 represents, on a relatively large scale, a portion 35 of the turret and the meeting portions of the telescope tubes in which are mounted respectively the object glass and eyepiece. Fig. 17^a represents a perspective view of the roll stud. Fig. 18 represents an end view of 40 the eyepiece and the mechanism for turning the telescope to the desired angle of declination. Fig. 19 represents an edge view, partly in section, of the operating mechanism included in Fig. 18. Fig. 20 represents a section on the plane indicated by line 45 20—20 in Fig. 18. Fig. 21 represents a section in the plane indicated by line 21—21 in Fig. 20. Fig. 22 represents a development 50 of a vernier for the operating mechanism included in Figs. 18 to 21. Fig. 23 represents an elevation of a portion of a gage ring for determining the position of the turret according to the desired right ascension. Fig. 24 represents an edge view of the same 55 portion of the ring included in Fig. 23. Figs. 25 and 26 represent diametrically opposite portions of the gage ring and diametrically opposite index devices adapted to coöperate with the ring. Fig. 27 represents 60 a section on the plane indicated by the line 27—27 in Fig. 25. Fig. 28 represents an elevation, partly in section, of a modified form of turret and mounting therefor. Fig. 29 represents a side elevation of a turret and mounting with a telescope of modified construction. Fig. 30 represents an elevation of the tube included in Fig. 29. Fig. 31 represents a section on the plane indicated by line 31—31 in Fig. 29. Fig. 32 represents a section in the plane indicated by line 32—32 in Fig. 29. Fig. 33 represents an elevation of an eccentric stud for adjusting the objective tube included in Figs. 29 to 31. Fig. 34 represents a section on the plane indicated by line 34—34 in Fig. 29. Fig. 35 represents a section in the plane indicated by line 35—35 in Fig. 34. Fig. 36 represents an end elevation of the eyepiece included in Fig. 34, and the operating mechanism for turning the objective tube to the 70 desired angle of declination. 75

The same reference characters indicate the same parts wherever they occur.

General structure.—Referring first to Fig. 1, the eyepiece of the telescope is indicated 90 at 40, and the tube for holding the object glass is indicated at 41. The telescope as a whole is movably mounted in a revoluble head or dome 42 hereinafter termed a turret. The turret is mounted to turn upon an 95 annular base 43 and is disposed so that its axis extends at an angle to the horizon, which axis is determined by the geographical location of the telescope. In the present instance, the observatory as illustrated 100 is intended for a latitude approximately 43 degrees 20 minutes north of the equator, and therefore the axis is disposed at an angle of 46 degrees 40 minutes from the zenith and points north. In other words, 105 the axis of the turret is parallel with the axis of the earth, and consequently I refer to the turret as being movable about the polar axis or an axis coincident therewith.

For the purpose of comfortably housing 110 the observer, the eyepiece 40 is effectually inclosed within the dome and the supporting structure wherein the temperature may be regulated as desired by the observer. The supporting structure housing, as illustrated 115 by Fig. 1, and also by Figs. 2, 3, 6 and 29, is constructed of any preferred waterproof materials, such, for example, as concrete. The walls 44 of the housing are preferably provided with suitable air spaces for the purpose of insulating; and, as shown by Fig. 1, the air spaces are the result of incorporating hollow tiles 44^a into the concrete. In this adaptation of the housing, the inclosure for the observer comprises an upper compartment 45 and a lower compartment 46. The floor of the upper compartment is shown as being substantially at the level of the ground, which level is indicated at 47. An observing platform, whereon the ob- 120

125

130

server may stand or be seated when using the telescope, is indicated at 48.

Glazed windows 49 are provided in the roof of the housing, and glazed apertures 42^x are provided in the turret. The temperature of the inclosure may be regulated as desired, by suitable means indicated conventionally at 50. A heating medium such as steam or hot water, or a cooling medium, 10 may be circulated through the radiator or coil 50. A supply pipe 51 is provided for delivering fresh air to the observer standing upon the platform. A blower, indicated at 52, is connected with the supply 15 pipe to force the supply of air through the supply pipe from any convenient source. The mechanism, hereinafter explained, for turning the turret 42 is driven by a suitable motor (in the present instance an electric motor) which may be governed by a rheostat 53 located within easy reach of the observer upon the platform 48. Electric 20 switches 54 are also located near the platform, whereby the observer may control the blower 52 and any other electrical devices, 25 such for example as lamps which are indicated at 55.

The dome or turret.—The turret, in which the telescope is mounted and which may 30 consist of a metallic casting, covered if desired with insulating material, rests upon rolls 42^a (Figs. 3^a, 4 and 17) which are mounted in the annular base 43. The rolls are free to turn upon eccentric portions 42^b 35 of studs 42^c (Figs. 17 and 17^a), and the studs are fixed with relation to the base by suitable means, such as set screws 42^d. By turning the roll studs, the rolls may be adjusted so that the turret will bear equally upon them 40 all, and the exact parallelism of the turret and the earth axes may be restored if the settling of the building has altered its position. The turret and base are provided with overlapping cylindric flanges 42^e and 43^e, 45 which flanges have only sufficient clearance to prevent contact and are adapted to prevent, to a great extent, the admission and escape of air.

The turret is formed with an annular 50 flange 42^f within the circle of the rolls 42^a. The inner cylindric surface of the flange 42^f bears upon driving rolls 56. (See Figs. 3^a, 4, 7 and 8.) In the present instance, there 55 are four of these driving rolls and they are disposed at suitable intervals near the top of the base 43 so that the weight of the inclined turret will secure the necessary traction. The rolls are formed upon or affixed to shafts 56^a and are supported by the base 56. As shown by Fig. 8, anti-friction 60 bearings 56^b are provided for the shafts and are arranged as closely as possible to the rolls so as to minimize the friction due to the weight of the turret. As shown by Figs. 3^a 65 and 4, the flange 42^f is engaged at diametri-

cally opposite points on the horizontal diameter by rolls 57 whose function is to prevent lateral movement of the turret and to hold the turret so that its axis will coincide with that of the base. The rolls 57 are 70 mounted upon adjustable blocks 57^a which in turn are mounted upon the base by pivot studs 57^b. Adjusting devices indicated conventionally at 57^c are adapted to engage the blocks to position the rolls. The base is 75 provided with a fourth set of rolls, which are indicated at 58 and are diametrically opposite those at 56. These rolls are arranged near the bottom of the base so as to engage the outer cylindric surface of the flange 42^f. The function of these rolls is to partially 80 support the weight of the turret so as to relieve the driving rolls 56 to some extent, but not to so great an extent as to deprive the rolls 56 of the requisite pressure for 85 driving the turret. The employment of the rolls 58 is not necessary for the support and operation of the turret, but they are provided only for structural reasons. The diameter of the flange 42^f and the internal 90 diameter of the base are such as to afford sufficient space for the observer to use the telescope in any position which it may occupy.

The telescope.—As shown by Fig. 17, the telescope comprises in addition to the objective tube 41, a tube 41^x for the eyepiece 40, which is perpendicular to the axis of the dome or turret or to a plane including said axis. The tubes 41 and 41^x are disposed at an angle of 90 degrees with relation to each other, and the rays which are refracted and bundled by the object glass at the free end of the tube 41 are reflected to the eyepiece by a reflector which in the present instance is in the form of a prism, indicated at 59 and located at the elbow of the tube 41, in the declination axis thereof. The tube 41^x is formed for the reception of a finder 60 to which the rays are reflected by another reflector which is likewise shown in the form 105 of a prism and which is indicated at 60^x. The reflector 60^x is mounted in a holder 60^a which projects beyond the tube 41 and is provided with an opening 60^b for the admission of rays.

The tubes 41 and 41^x are fixed with relation to each other. A sleeve 61 surrounds the sleeve 41^x and is affixed in bearings 61^x in the turret. The tube 41^x bears in and turns relatively to the sleeve 61, the tube being arranged so that its axis intersects and is disposed as stated at an angle of 90 degrees to the axis of the turret or to a line parallel thereto.

The turret is provided with a counterweight which is disposed to counteract the weight of the telescope so that the turret will turn freely. The free end of the tube 41 is supported or braced by a trussed connection indicated at 62 in Figs. 1, 5 and 6. 130

This connection extends to a cap or head 62^x which is rotatably mounted in any suitable manner upon a tubular pivot 62^a. This pivot extends into the turret in alinement with the tube 41^x at a point diametrically opposite the latter and is suitably secured in bearings indicated in Fig. 3^a at 62^b. An arm 62^c affixed to the head 62^x, and constituting at it were an extension of the arm or brace 62, is provided with a weight 62^d which is adapted to balance the tube 41 so that it will be free to swing about the axis of the tubes or pivots 41^x and 62^a. This weight also tends to balance the turret so that the latter will be free to turn about its axis. In the present instance, the tube 41 requires a counterweight slightly heavier than that required by the turret to counteract the weight of the tube, and for this reason the turret is provided with counterweights, such as that indicated at 62^e, so that it may balance in all positions.

Mechanism for securing angle of declination.—The mechanism for turning the telescope relatively to the turret to the desired angle of declination is shown by Figs. 17 to 21. A worm wheel 63 is keyed or otherwise affixed to the tube 41^x. This worm wheel is engaged by two worms 64 which are mounted upon the turret at diametrically opposite points with relation to the center of the wheel and which are operated in unison. Referring to Figs. 20 and 21, each worm is formed upon a sleeve 64^a to which is keyed the hub of a spiral gear 64^b. The two spiral gears 64^b intermesh with spiral gears 65, both of which are affixed upon a transverse shaft 65^a. A third spiral gear 65^b, disposed midway between the ends of the shaft, meshes with a driving gear 66 which is affixed to the shaft 66^a. The shaft is provided with a hand wheel 66^b which is so located that the observer may operate it while looking into the eyepiece.

The rim of the worm wheel 63 is provided with a gage or scale consisting of marks 63^a which divide the circle of the wheel into 360 degrees. Fig. 19 shows two index fingers represented by dotted lines and indicated at 63^b. These fingers are arranged diametrically opposite each other and overhang the worms 64. Their location is indicated in Fig. 18, and they are adapted to coöperate with the scale 63^a upon the wheel. A vernier is provided for enabling the observer to adjust the telescope more accurately than would be possible by means of the marks 63^a alone. The vernier, as represented by Fig. 22, is adapted to enable the observer to adjust the telescope within one second of the desired angle. As shown by Fig. 20, the sleeve 64^a is formed with a flange 64^c which extends outside the hub of the gear 64^b. This flange is provided with the scale 64^d, (see Fig. 18). The end of the flange 64^c

abuts against an adjustable collar 64^e upon which the coöperative scale 64^f of the vernier is provided. The collar 64^e is held (see Fig. 21) by set screws 64^g in fixed relation to a bracket 64^h, in which the worm is mounted by means of a rod or spindle 64ⁱ. The gearing for turning the worm wheel 63 is such that one revolution of the worms 64 is equal to one degree of angular or rotative movement of the wheel 63. The vernier 70 enables the observer to adjust the worm sleeve with great precision; and the movement of the sleeve, being greatly reduced in transmission to the wheel 63, gives an adjustment as nearly accurate as could be desired. The function of the adjusting screws 64^g is to obtain accuracy in positioning one of the elements of the vernier, and, after the desired position has once been found, it is not necessary thereafter to change it. 80

A modified form of mechanism for moving the objective tube to the desired angle of declination is illustrated by Figs. 34, 35 and 36, hereinafter described.

Turret moving mechanism for right ascension.—A motor is provided for turning the turret to the desired position to obtain the angle of ascension and for driving the turret slowly to neutralize the earth's diurnal motion. The gearing for driving the rolls 56 is 90 shown best by Figs. 3^a, 7 and 8. Referring first to Figs. 7 and 8, a gear 56^c is keyed or otherwise affixed to each of the roll shafts 56^a. Two of these gears mesh with a pinion 56^d which is loosely mounted upon one of the 100 intermediate shafts 56^a. The other two gears 56^c mesh with another pinion 56^d which is likewise loosely mounted upon the other intermediate shaft 56^a. Each of the two pinions 56^d is affixed to or compounded with a 105 gear 56^e; and the gears 56^e mesh with small gears 56^f which, in the present instance, are formed upon the same hub or sleeve as indicated at 56^g in Figs. 3^a, 8, 9 and 10. The sleeve is mounted upon and affixed to a 110 power shaft 67, the axis of which is parallel to the axis of the turret. By this arrangement, the roll shafts are rotated synchronously in the same direction.

The shaft 67 may be driven at either of 115 two speeds by the same motor. The bevel gear 68 is affixed to the shaft 67 for driving the shaft at a relatively fast speed to enable the observer to quickly find the approximate angle of ascension of a star or planet. Friction clutch members 69 and 69^a are mounted upon the shaft 67 and are adapted to be driven at a relatively slow speed to impart rotation to the turret to counteract the diurnal motion of the earth. 120

The gear 68 (see Figs. 3^a and 10) meshes with a bevel gear 68^a which is affixed at the upper end of a vertical shaft 70 hereinafter termed the fast-speed shaft. This shaft is preferably made in two sections, the lower 130

section of which is indicated at 70^a. A suitable friction coupling device 70^a (which it is not necessary to describe in detail) is provided for connecting the abutting ends of the two shaft sections (see Fig. 16), the function of which is to avoid damage in case the movement of the turret is obstructed. Gearing is provided for driving the shaft section 70^a in either direction. As shown by Figs. 10 and 12, a worm gear 70^c is mounted upon the section 70^a near its lower end. This worm gear is loose upon the shaft and is provided with clutch teeth 70^a. A clutch 70^e (Fig. 14) is splined upon the shaft and is provided with clutch teeth 70^a adapted to be moved to and from driving engagement with the teeth on the gear 70^c. The gear 70^c is driven by a worm 71 affixed to a shaft 72. This shaft may be regarded as the prime power shaft, and it may be driven by any suitable means. It is preferred, however, to locate the source of power outside the observatory housing, for the purpose of avoiding as far as possible all noise incident to the working of a motor.

As shown by Fig. 2, a motor 73 is installed in a separate housing 74 apart from the housing of the observatory. The housing 74 may be wholly or partially disposed below the ground level. The driving connection between the motor and the power shaft 72 is, in the present instance, a belt 75 which passes over a driving pulley 73^a on the motor shaft and over a pulley 72^a on the shaft 72. A sleeve or casing 72^b is provided for inclosing the shaft 72 and inclosing the electric conductors 73^x which lead to the motor. The shaft 72 is preferably made in two sections, and the sections are coupled by a coupling device 72^c adapted to compensate for any angular relation of the two sections. The several worms and gears and toothed clutch members hereinbefore described are inclosed in a gear case 72^d standing on the floor of the observatory.

In order to provide for turning the turret in a reverse direction, a second worm gear 76 is arranged to engage the worm 71. The latter gear is loosely mounted upon a counter-shaft 76^a and is provided with clutch teeth 76^b. A second clutch sleeve 76^c is splined upon the shaft 76^a and is provided with clutch teeth 76^b adapted to be moved to and from engagement with the teeth on the gear 76. An oscillatory shipper 77 connected with the two clutch sleeves is affixed upon a rock shaft 77^a and is adapted to couple either of the clutch sleeves with its respective worm gear. The two worm gears are, of course, rotated in opposite directions. Referring to Figs. 10 and 13, pinions 70^c and 76^d are affixed respectively to the shaft section 70^a and to the countershaft 76^a. An intermediate gear 76^e is adapted to transmit rotation from the pinion 76^d to the pinion

70^c. Now, therefore, when one of the clutch sleeves is placed in operative engagement with one of the worm gears, the shaft 70^a will be driven in one direction; whereas, if the other clutch sleeve is placed in engagement with the other worm gear, the shaft will be driven in the opposite direction. This motion will be transmitted through the friction coupling 70^b and the train of gears to the driving rolls 56, and the turret will be rotated rapidly in one direction or the other.

The rock shaft, which carries the shipper 77, is provided with a spiral gear 77^b. This gear engages a spiral gear 77^c affixed to a vertical shaft 77^d, which is provided with manually operative means whereby the shipper may be moved to effect the desired connection of the clutches. As shown by Fig. 10, a hand lever 78 is pivotally connected at 78^a to a collar 78^b which is loosely mounted upon the upright shaft 77^d and is disposed between collars 78^c and 78^d, both of which are affixed to the shaft. The collar 78^d is provided with radial teeth 78^e which are adapted to be engaged by a tooth 90 or projection 78^f on the lever 78. As shown by Fig. 10, this lever occupies an inoperative position wherein it is in a position out of the way of the observer. Both clutch sleeves are disengaged from the worm gears with which they are adapted to co-operate. When it is desired to use the fast-speed shaft to turn the turret in one direction or the other, the desired clutch may be connected by swinging the lever 78 about its pivot so as to move the tooth 78^f between two teeth 78^e of the collar 78^d, this bringing the lever 78 in a radial position with relation to the shaft 77^d and operatively connecting the lever with the shaft so that the shaft can be turned slightly in either direction by swinging the lever laterally. A slight turning of the shaft is sufficient to effect the desired movement of the shipper 77. When the fast-speed shaft is no longer needed for driving the turret, both clutch sleeves may be left disconnected as shown, and the lever 78 may be swung out of the way to the position which it occupies in Fig. 10.

The main driving shaft 72 is provided with a second worm, indicated at 79 in Figs. 10 and 12. This worm, when driven at the right speed, effects a movement of the turret which counteracts the diurnal motion of the earth. The speed of the motor can, of course, be regulated by the rheostat 53. Rotation is transmitted from the worm to a worm gear 79^a which is affixed to the vertical shaft 79^b. The upper end of this shaft is connected by gearing to the lower end of a shaft 79^c. As shown by Fig. 10, the lower end of the shaft 79^c is formed with a socket or bearing 79^x to receive the upper end of the shaft 79^b whereby the two shafts are kept in alignment. The upper end of the

shaft 79^c is provided with a worm 80 which engages a gear 80^a formed upon or affixed to the clutch member 69^a hereinbefore mentioned. A pinion 79^d affixed to the shaft 79^b 5 engages pinions 79^e which in turn engage another internal gear tooth 79^f formed upon a member 79^g affixed to the shaft 79^c. The pinions 79^e are mounted upon a disk 79^h through which the shaft 79^b extends loosely. 10 When the disk 79^h is held stationary, the shaft 79^c is driven at a much slower speed than the shaft 79^b; and this motion, when the clutch members 69 and 69^a are connected, is transmitted to the turret. 15 The disk 79^h is a device for correcting the position of the turret whenever the speed of the driving mechanism as imparted by the shaft 79^c does not accurately counteract the earth's diurnal motion. As shown by Fig. 20 20 11, the rim of the disk 79^h is provided with teeth 81, and these teeth are adapted to be engaged by a pin or projection 81^a projecting from a rock shaft 81^b. The rock shaft is provided with a hand wheel 81^c whereby 25 the pin may be moved to or from engagement with the teeth 81. The pin is engaged between two of the teeth, as shown by Fig. 11, in order to arrest the rotation of the disk 79^h, so that the pinion 79^d may drive 30 the internal gear 79^f. So long as the diurnal movement of the telescope follows the planet under observation, the disk remains locked; but, if the movement of the telescope should be too fast or too slow, the position of the 35 telescope may be corrected, first by turning the hand wheel 81^c to unlock the disk and thereafter arresting the movement or increasing the movement of the shaft 79^c. This, of course, may be done without stopping the motor. When the disk 79^h is unlocked, it will revolve with the shaft 79^b so 40 45 that the pinions 79^e will describe a planetary movement within the gear 79^f without driving the latter. A hand wheel 81^d is loosely mounted upon the shaft 79^b and is supported by a collar 81^e affixed to the shaft. The hand wheel is coupled in any suitable way with the hub of the disk 79^h so that the disk may be turned by means of the hand 50 55 wheel. As shown by Figs. 10 and 11, the hub of the hand wheel is provided with a pin 81^f which projects into a recess in the hub of the disk. If the movement of the shaft 79^c as effected by the motor is too slow, it may be increased by turning the hand wheel 81^d after first disengaging the pin 81^f from the teeth 81. On the other hand, if the movement of the shaft 79^c is too fast, 60 65 the position of the telescope may be corrected by merely disengaging the pin 81^f from the teeth 81 for a sufficient length of time to enable the earth to overtake the already advanced position of the telescope.

The correcting device is within easy reach 65 of the observer, so that it may be manipu-

lated while a planet is under observation, and the observer may be enabled to time the operation of the correcting device without looking away from the telescope. The handle 78 and the hand wheel 81^c are likewise 70 accessible without necessitating the movement of the observer away from the eye-piece.

A modified form of correcting device is shown by Fig. 11^a, (see sheet bearing Fig. 3^a). This device comprises a worm 81^x on the shaft 81^b in place of the pin 81^a. The worm not only serves to hold the disk 79^h against rotation, but it is adapted to impart rotation in either direction, thus dispensing with the necessity of the hand wheel 81^d. 80 In other words, the worm is adapted to perform the function of the pin 81^a as well as the function of the hand wheel 81^c.

The clutch members 69 and 69^a are provided with operating mechanism whereby it 85 is impossible to couple them when the shaft 70 is being used for turning the turret. As shown by Fig. 9, the clutch member 69^a is loosely mounted upon the shaft 67, and the clutch member 69 is slidably connected 90 with the shaft by a pin 69^b. This pin extends through an elongated transverse opening 69^c formed in the shaft. This form of connection enables the clutch member 69 to move longitudinally with relation to the 95 shaft, but holds one against rotation relatively to the other. The shaft is bored for the reception of a clutch-operating rod 69^d, and the pin 69^b extends transversely through this rod so as to be shifted by it. A spring 100 69^e arranged within the shaft is compressed so as to act against the inner end of the rod with the effect of normally holding the clutch member 69 in clutched engagement with the member 69^a. A hand lever 82 accessible to the observer is adapted to engage the outer end of the rod, with the effect of disconnecting the clutch members. This lever is pivoted at 82^a, and, as shown by Fig. 15, is provided with a laterally extending pin or projection 82^b the end of which is beveled. This projection is adapted to operate with a similar pin or projection 82^c on an arm 82^d affixed to a part of the stationary frame work. The pins 82^b and 82^c 110 115 occupy the relation shown by Fig. 15 when the clutch member 69 and 69^a are coupled as shown by Fig. 9. The lever 82 is formed with a projection 82^d which is adapted to enter an opening formed in an arm 82^e affixed at the upper end of the shaft 77^d. As shown by Fig. 10, the shaft 70 is disconnected from the source of power, because both of the clutch sleeves 70^e and 76^e are disconnected from the worm gears which 120 125 have corresponding clutch teeth. Whatever movement the shaft 70 receives under these conditions it receives through the gear 68 and clutch members 69 and 69^a. When the projection 82^d occupies the opening in the 130

arm 82^e, the shaft 77^d is locked so that it is impossible to move either of the clutch sleeves 70^e and 76^e into driving position. At this time the friction clutch members 69 and 69^a are connected, because they are released by the lever 82. When it is desired to drive the turret by means of the shaft 70, it is first necessary to unlock the shaft 77. This can be done only by withdrawing the projection 82^d from the arm 82^e and at the same time uncoupling the clutch members 69 and 69^a. When the hand lever 82 is moved to unlock the shaft 77^d, the projection 82^b having the beveled end is moved downwardly past the projection 82^c, the beveled faces of the projections causing lateral flexure of the lever 82 until the projection 82^b passes wholly below the projection 82^c. The lever may then spring back to its normal lateral position wherein the projection 82^b will engage the under surface of the projection 82^c and lock the lever in such position as to hold the clutch members 69 and 69^a apart. The turret thereupon becomes wholly disconnected from the source of power, and may be driven through the fast-speed shaft 70 by manipulating the clutch lever 78 hereinbefore described. Whenever either of the toothed clutch sleeves 70^e and 76^e is in driving engagement with the corresponding worm gear, the position of the arm 82^e prevents the release of the hand lever 82 and consequently prevents driving connection through the friction clutch members 69 and 69^a. In order to again drive the turret through the medium of the friction clutch members, it is first necessary to disconnect both of the toothed clutch members in order to place the arm 82^e in position to receive the projection 82^d on the lever 82. The lever 82 may then be released from the projection 82^c by a slight lateral flexure of the lever, whereupon it may be restored to the position shown and the friction clutch members may be coupled by the spring 69^e.

Hour circle.—An annular gage or ring, hereinafter termed the hour circle, is mounted upon the turret and is adapted to be used with reference to sidereal time to enable the observer to set the turret at a position corresponding to the desired right ascension. This hour circle is mounted upon the turret, as shown best by Figs. 3^a and 4^a, and is indicated at 83. It is formed with a flange 83^a and is supported by a plurality of studs 83^b which project inwardly from a flange formed on the turret (see Fig. 27). The inner face of the ring is provided with a scale having marks 83^c (Fig. 24) which divide the circle into 24 divisions each representing one hour of time, and subdivide the hours into minutes. The ring is free to be rotated manually with relation to the turret and is used in conjunction with a stationary index mounted upon the base and

with two indexes mounted on and movable with the turret. The stationary index consists of a block 84 mounted in a bracket 84^a by trunnions 84^b. The bracket is affixed to the base 43 in such manner that the block 84 will bear against the under flat face of the ring, and it is disposed at the zenith, *i. e.* in the vertical plane of the axis of the turret at the highest point of the ring. A mark 84^c, hereinafter termed the zenith point, is provided on the block 84 and is adapted to be read in conjunction with the scale on the hour circle. The trunnions 84^b are screw-threaded in the bracket 84^a and are adapted to position the block 84 laterally so as to determine accurately the location for the zenith point.

The movable index members on the turret are shown in detail in Figs. 25, 26 and 27, and their positions are shown by Figs. 3^a and 4^a. Each movable index comprises an adjustable member 85 and a bracket 85^a. The brackets are affixed to the turret at diametrically opposite points, and the members 85 are connected to the brackets by trunnions 85^b. Each member 85 is provided with an index mark 85^c which is adapted to be read in conjunction with the scale on the hour circle. The trunnions 85^b are adapted to adjust the members 85 laterally so as to locate the marks 85^c at precisely 180 degrees from each other and ninety degrees from the axis of the eyepiece. In finding a celestial body, the hour circle is moved to bring the figure on the scale, indicating the hour, minute and second at which said body is at zenith, opposite one of the indexes on the turret, and then the turret is rotated to bring the figure on the hour circle, indicating the then sidereal time, to the zenith point on the base. Such minute adjustment as may be necessary may be made by the hand wheel 81^d in the manner hereinbefore explained.

As heretofore stated, the telescope is mounted in such manner as to effectually protect the observer from out-of-door conditions. It is obvious, however, that the telescope may be mounted and operated in the manner explained without requiring a closed compartment for the observer. For example, Fig. 28 illustrates a construction wherein the observer is not inclosed. This construction includes means for adjusting the base for the turret so as to locate the axis of the turret in exact parallelism with the polar axis of the earth. The base 43, in this instance, is provided with adjusting screws 43^a which engage the foundation for the turret. By means of these screws, it is possible to adjust the base, and consequently the turret, with relation to the foundation so as to cause the axis of the turret to extend in the desired direction according to the latitude of the ob- 130

servatory. The turret, as shown by this figure, is of simpler construction than that hereinbefore considered, and it is operated by mechanism of comparatively simple construction. An internal cylindric surface of the turret bears against a single driving roll, indicated at 56^a. This roll is affixed to a shaft 56^c which is mounted in suitable bearings afforded by the base. A gear 80^x is affixed to the shaft and is driven by a worm 80^y mounted upon a vertical shaft 79^x. Any desired mechanism may be provided for driving the shaft 79^x at the desired speed and in the desired direction.

15 Figs. 29 to 35 illustrate a modified form of telescope which embodies some of the features of the telescope hereinbefore described, and it is mounted in a turret in the manner explained. In this modified form the objective tube is indicated at 41^a. The inner end of the tube is affixed to a rotatable carrier 41^b. The eyepiece, indicated at 40, is fixed with relation to the turret, and the objective tube is therefore movable with relation to the eyepiece. The eyepiece is mounted upon a tube 41^c which is affixed in the turret. The outer end of the tube affords a bearing for an annular flange 41^d on the holder 41^b. A flange 41^e, formed on the tube, is engaged by an annular flanged member 41^f which has screw-threaded connection with the holder 41^b. A reflector 59^x, here shown in the form of a prism, is adapted to reflect the rays from the tube 41^a through tube 41^c to the eyepiece. The holder 41^b is provided with teeth 86 arranged to form an internal gear. This gear is engaged by pinions 86^a which are affixed to shafts 86^b. The shafts are parallel and are diametrically opposite with reference to the axis of the tube 41^c. The bearings for the outer ends of the shafts are afforded by the flange 41^e, while the bearings for the inner ends are afforded by a bracket 87. The bracket is affixed to the turret and affords bearings for a transverse shaft 86^c. This shaft is provided with worms 86^d which coöperate with worm gears 86^e affixed respectively to the shafts 86^b. A spiral gear 86^f affixed to the transverse shaft coöperates with a spiral gear 88 affixed upon a shaft 88^a. The shaft carries a hand wheel 88^b whereby the various gears and shafts may be operated in unison to turn the holder 41^b. The objective tube 41^a is circular at its outer end and elliptical in its cross section at its inner end. One of the transverse partitions for breaking up the reflected rays within the tube is indicated in Fig. 32 at 89.

60 The trussed connection 62 for supporting the outer end of the tube is connected by studs such as that shown in Fig. 33, whereby the position of the tube may be corrected to eliminate any defect due to sagging. The

connection 62 is provided with a yoke 62^a the ends of which are connected to the tube by studs 62^b. The studs are formed with eccentric portions 62^c which bear in blocks 62^d affixed to the tube. The outer ends of the studs 62^b are provided with angular heads 62^e whereby a wrench may be employed to turn the studs to the desired position. The shanks of the studs are screw-threaded, as indicated at 62^f, to receive clamping nuts 62^g whereby they may be securely held after being adjusted.

It will be apparent to astronomers from the foregoing description that I have provided an equatorial telescope (that is one having a mounting consisting of two pivotal joints, one called the polar axis, parallel to the earth's axis, and the other called the declination axis and being at right angles to the polar axis or to a line parallel therewith) which is unlimited in its range and which is efficient, not only optically, but also in point of mechanical precision, and furthermore in which there is no necessity of requiring a temperature in the dome equal to that of the external atmosphere. The range of observation is not limited by the base structure or housing since the tube may be directed to any point in the visible heaven. The methods of mounting the dome in circular and cylindrical tracks, and pivoting and counterpoising the tube, enable them to be maintained rigidly and without vibration; and the power-transmitting mechanisms, within convenient control of the operator, permit the dome and tube to be positioned with ease and precision. In this connection I may point out that the turret or dome constitutes a circular ring bearing or polar pivot for the telescope, as distinguished from an arbor about which the telescope may be swung. While an arbor of small diameter mounted in separated bearings furnishes a reliable center control about which to move a body for accurate angular position, yet in a large telescope, the necessary delicacy of poise is not favorable for stability of control. In the present case, however, the turret has a circular plane surface which may be engaged at points remote from each other to hold the polar axis of the turret in perfect parallelism with the earth's axis, and a cylindrical surface with which may be engaged the rolls or guides which prevent lateral movement of the turret and insure a fixity of the polar axis, thus making it possible to control the motion and angular position of the turret and tube around the polar axis with the necessary accuracy.

In lieu of supporting the circular and cylindrical edge or rim of the turret by the two sets of rolls, it might be fitted in a hollow ring bearing, with or without interposed

antifriction rolls or balls. As described, the two sets of rolls constitute, as it were, circular guideways or tracks.

Of course the exact form of turret and base or housing are not essential, since they may be varied indefinitely to suit particular geographical locations, particular dimensions and other forms of telescope. In general any form of turret or dome, movable about the polar axis and providing a hollow space large enough to accommodate the observer's head and shoulders, would answer one of the purposes of the invention.

The telescope itself is a refractor, with the reflecting prism at the elbow of the tube, close to the eyepiece, and consequently overcomes the optical loss that characterizes the telescopes in those observatories in which an attempt is made to insure the comfort of the observer. Thus the rays of light are delivered from the object glass to the ocular by the employment of a single prism which, on account of its location, may be of small diameter, since the bundle of rays at that point requires an area approximately only one sixteenth of the area of the object glass. Consequently by avoiding the use of large reflecting mirrors, I also avoid the mechanical difficulties encountered in holding such mirrors without flexure. The tube, being pivoted at one end, and having its free end supported and braced by the counterpoise, is easily controlled and its stability is maintained.

In the specification and claims, I have used the term "polar axis," in referring to the axis of rotation of the dome or turret which supports the telescope tube, as meaning either the exact axis of rotation of the earth or a line parallel therewith. On account of the practically infinite distances between the earth and the nearest celestial bodies, the fact that the axis of rotation of the turret is really offset from the earth's axis need not be taken into account, on the principle that parallel lines meet in infinity. Consequently it is not necessary for the axis of the turret to coincide with the axis of the earth (*i. e.*, be located at the north or south pole), although it may be helpful for the layman reading this specification to consider the observatory as being located at the north pole. Nor, on the same principle, is it necessary for what I have termed the axis of declination of the tube to be perpendicular to the polar axis of rotation of the turret, so long as it is perpendicular to a line parallel to said polar axis.

Having thus explained the nature of my said invention and described a way of constructing and using the same, although without attempting to set forth all of the forms in which it may be made or all of the modes of its use, what I claim is:

1. The combination with a telescope, of a

circular ring bearing therefor having an axis parallel with the earth's axis.

2. A construction for astronomical observations, comprising a telescope tube and a rotatable turret which constitutes its polar pivot. 70

3. A construction for astronomical observations having a hollow pivotal joint consisting of a circular ring-like track.

4. A construction for astronomical observations, comprising a telescope tube, a hollow turret movable about an axis coincident with the polar axis, and means for attaching said tube to said turret. 75

5. A construction for astronomical observations, comprising a turret rotatable about an axis coincident with the polar axis, and an objective tube pivoted to the turret to move about an axis which is perpendicular either to the first-mentioned axis or to a line 85 parallel thereto.

6. In a construction for astronomical observations, a dome mounted to rotate about an axis which is coincident with the polar axis. 90

7. In a construction for astronomical observations, a dome rotatable about an axis which is coincident with the polar axis, a telescope tube external to said dome but pivoted thereto to move about its declination axis. 95

8. In a construction for astronomical observations, a dome rotatable about an axis which is coincident with the polar axis, a telescope tube external to said dome but pivoted thereto to move about its declination axis, and an eyepiece inside said dome arranged in substantial alinement with said declination axis. 100

9. In a construction for astronomical observations, a dome rotatable about an axis which is coincident with the polar axis, a telescope tube external to said dome but pivoted thereto to move about its declination axis, an eyepiece inside said dome arranged in substantial alinement with said declination axis, and a reflector in the tube at the elbow thereof. 105

10. In a construction for astronomical observations, the combination of a dome movable about an axis which is coincident with the polar axis, a telescope tube external to said dome, a hollow pivot connecting said tube to said dome to permit said tube to move about its axis of declination, and means within the dome for swinging said tube about its pivot. 115

11. In a construction for astronomical observations, the combination with a base structure and a turret movable thereon about an axis which is coincident with the polar axis, said base structure and turret constituting a compartment for the observer closed to the external atmosphere, a telescope tube external to said turret but piv- 125

oted thereto to move about its axis of declination, and an eyepiece extending into the turret.

12. In a construction for astronomical observations, the combination with a hollow annular bearing or guideway, of a hollow turret mounted thereon to move about an axis coincident with the polar axis, and a telescope tube supported by said turret.

10 13. In a construction for astronomical observations, a rotatable turret, and a telescope tube external to said turret and supported on said turret.

14. In a construction for astronomical observations, a turret rotatable about an axis coincident with the polar axis, a telescope tube, and means for pivoting the end of the tube opposite the object glass to said turret to move about an axis of declination perpendicular to a plane including the polar axis.

15. In a construction for astronomical observations, the combination of a base structure, a turret movable thereon about an axis coincident with the polar axis, said base and turret constituting a compartment closed to the external atmosphere, a telescope tube external to said turret but pivoted thereto at one end and having the opposite end provided with an object glass, the axis of movement of said tube being perpendicular to a plane including said polar axis, an eyepiece within said turret, means controlled within said turret for rotating said turret, and means within said turret for oscillating said tube.

16. The combination with a telescope tube, a hollow pivot for one end thereof to permit said tube to be swung about an axis of declination, and a counterweighted arm pivoted to move about said axis and connected to the free end of said tube.

17. In a construction for astronomical observations, the combination of a rotatable annular support; a telescope tube pivotally attached at one end to one side of said annular support; and a counterweighted brace or strut pivotally attached to the other side of said support and connected to the free end of said tube.

18. In a construction for astronomical observations, the combination of an annular support rotatable about an axis coincident with the polar axis, a telescope tube pivotally attached at one end to one side of said support and movable about a declination axis perpendicular to a plane including said polar axis, and a counterweighted brace or strut pivotally attached to the other side of said support and connected to the free end of said tube, the axis of said brace or strut coinciding with said declination axis.

19. In a construction for astronomical observations, an annular base, a rotatable hollow turret thereon, said turret having its

axis of rotation parallel to the earth's axis, a telescope tube, a hollow pivot connecting one end of said tube to said turret to move about an axis perpendicular to a plane including the first-mentioned axis, a reflector located at the elbow formed by said tube and said pivot, and an eyepiece in the turret for receiving the reflected rays of light.

20. In a construction for astronomical observations, a telescope tube and a mounting therefor comprising an annular support rotatable about an axis coincident with the polar axis and having a plane face and a cylindrical portion, in combination with a stationary base having means for engaging said face and said cylindrical portion, in consequence of which the plane face maintains the axis of rotation in perfect parallelism with the earth's axis and the cylindrical portion holds said support against lateral movement.

21. In a construction for astronomical observations, a telescope tube, an inclined base or foundation, an inclined annular support for the tube rotatable thereon about an axis coincident with the polar axis and having a flat bearing face and a cylindrical bearing portion, rolls on said base for engaging said flat face, and driving and supporting rolls engaging said cylindrical portion.

22. In a construction for astronomical observations, an annular base, a rotatable annular support movable about an axis coincident with the polar axis, a telescope tube mounted on said support, an hour circle consisting of a graduated ring rotatably mounted in said support, and indexes on the base and the support.

23. In a construction for astronomical observations, an annular base, a hollow turret rotatable about an axis coincident with the polar axis, a telescope tube pivoted to said turret, an hour circle consisting of a graduated ring rotatably mounted on said support in a plane to which said polar axis is perpendicular, an index on said base and an index on said turret.

24. A construction for astronomical observations comprising a base having an annular track or guideway, an annular support rotatable on said track, a telescope tube pivoted to said annular support to move about a line perpendicular to a plane including the axis of rotation of said support, and an eyepiece projecting within said support.

25. A construction for astronomical observations comprising a support, a hollow pivot on said support, a telescope tube having its end supported by said pivot and arranged radially of said pivot, a toothed annulus rigidly connected to said tube, and gearing for rotating said annulus and thereby said tube about the median line of said pivot.

26. A construction for astronomical ob-

- servations comprising a support, a hollow pivot on said support, a telescope tube having its end supported by said pivot and arranged radially of said pivot, a toothed annulus rigidly connected to said tube, power-transmitting gears engaging said annulus, and a device for transmitting power to both said gears simultaneously. 5
27. A construction for astronomical observations comprising a support, a hollow pivot on said support, a telescope tube arranged radially of said pivot and having one end supported thereby with its other end free, a toothed annulus rigidly connected to 10 said tube, power-transmitting gears engaging said annulus, a hand wheel, and operative connections between said hand wheel and said gears. 15
28. In a construction for astronomical observations, an inclined base, an inclined annular support thereon rotatable about an axis coincident with the polar axis, a telescope tube pivotally mounted on said support to move about a declination axis, rotary drivers on which said support is hung, and means for engaging said annular support and holding it against lateral movement. 25
29. In a construction for astronomical observations, an inclined base, an inclined annular support thereon rotatable about an axis coincident with the polar axis, a telescope tube pivotally mounted on said support to move about a declination axis, rotary drivers on which said support is hung, gearing connecting said drivers to cause them to rotate in the same direction and in peripheral unison, and a power shaft for imparting power to said gearing. 35
30. In a construction for astronomical observations, a telescope tube, a turret supporting said tube and rotatable about an axis coincident with the polar axis, a power shaft, and mechanism controlled within said 40 turret and operated by said power shaft for rotating said turret in either direction. 45
31. In a construction for astronomical observations, a telescope tube, a turret supporting said tube and rotatable about an axis coincident with the polar axis, a power shaft, mechanism controlled within said 50
- turret and operated by said power shaft for rotating said turret in either direction, and means by which the turret may be manually corrected as to angular position. 55
32. A construction for astronomical observations comprising a base structure, a turret thereon rotatable about an axis coincident with the polar axis, said base structure and turret forming a compartment for the observer, an eyepiece within the turret, a telescope tube pivoted to said turret to swing about a declination axis, a power shaft, power-transmitting connections between said shaft and said turret to impart a reverse diurnal rotation to said turret, power-transmitting connections for imparting a rapid rotation to said turret to position it, and manually operated controllers within said compartment for controlling the operation of said power-transmitting connections. 60
33. A construction for astronomical observations comprising a base structure, a turret thereon rotatable about an axis coincident with the polar axis, said base structure and turret forming a compartment for the observer, an eyepiece within the turret, a telescope tube pivoted to said turret to swing about a declination axis, a power shaft, power-transmitting connections between said shaft and said turret to impart a reverse diurnal rotation to said turret, power-transmitting connections for imparting a rapid rotation to said turret to position it, manually operated controllers within said compartment for controlling the operation of said power-transmitting connections, and means within said compartment for moving said tube about its axis of declination. 65
34. In a construction for astronomical observations, a dome rotatable about an axis coincident with the polar axis, a telescope tube mounted on the dome, and mechanism for rotating the dome and thereby the tube about said axis. 70
